CLAIM

The ornamental design for a propeller guard as shown and described.

DESCRIPTION

FIG. 1 is a front perspective view of a propeller guard showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of an indicated portion of FIG. 1;

FIG. 10 is an enlarged view of an indicated portion of FIG. 2; and,

FIG. 11 is an alternate front view of the propeller guard showing its ability to cover a propeller.

The broken lines in FIGS. 1-10 illustrate portions of the propeller guard that form no part of the claimed design. The dot dash broken lines in FIGS. 1, 2, 9, and 10 illustrate the periphery of the enlarged views of the propeller guard and form no part of the claimed design. The broken lines in the form of a propeller in FIG. 11 depict environmental subject matter and form no part of the claimed design.
